CLAIM

The ornamental design for a combined lamp with lamp holder, as shown and described.

DESCRIPTION

FIG. 1 is a front view of a combined lamp with lamp holder, showing our new design;

FIG. 2 is a back view of FIG. 1;

FIG. 3 is a left view of FIG. 1;

FIG. 4 is a right view of FIG. 1;

FIG. 5 is a top view of FIG. 1;

FIG. 6 is a bottom view of FIG. 1;

FIG. 7 is a front perspective view of FIG. 1;

FIG. 8 is a rear perspective view of FIG. 1;

FIG. 9 is a front view of a combined lamp with lamp holder as shown in FIG. 7;

FIG. 10 is a back view of FIG. 9;

FIG. 11 is a left view of FIG. 9;

FIG. 12 is a right view of FIG. 9;

FIG. 13 is a top view of FIG. 9;

FIG. 14 is a bottom view of FIG. 9;

FIG. 15 is a front perspective view of FIG. 9;

FIG. 16 is a rear perspective view of FIG. 9;

FIG. 17 is a front view of a combined lamp with lamp holder as shown in FIG. 7;

FIG. 18 is a back view of FIG. 17;

FIG. 19 is a left view of FIG. 17;

FIG. 20 is a right view of FIG. 17;

FIG. 21 is a top view of FIG. 17;

FIG. 22 is a bottom view of FIG. 17;

FIG. 23 is a front perspective view of FIG. 17; and,

FIG. 24 is a rear perspective view of FIG. 17.

The broken lines are included for the purpose of illustrating portions of the combined lamp with lamp holder and forms no part of the claimed design.
